UNITED STATES PATENT OFFICE.

PETER DUCHSCHER, OF CHICAGO, ILLINOIS.

MECHANICAL MOVEMENT.

SPECIFICATION forming part of Letters Patent No. 662,061, dated November 20, 1900.

Application filed December 28, 1899. Serial No. 741,839. (No model.)

To all whom it may concern:

Be it known that I, PETER DUCHSCHER, a citizen of the United States, residing at Chicago, in the county of Cook and State of Illinois, have invented certain new and useful Improvements in Mechanical Movements, of which the following is a specification.

The present invention relates to that class of organisms used in the transmission of power in which the force is multiplied in transmission; and the object of the invention is to provide an improved organism of this class, one especially adapted for the utilization of manual power in the production of heavy strains. The invention relates solely to the transmitting mechanism and has nothing whatever to do with the character of the machine in which the power is utilized further than that it contemplates the presence of such accessories as will make the improved mechanism available for the production of some useful result. I may mention, however, that the invention is especially adapted for use in presses of various kinds, lifting-jacks, windlasses, and many other machines intended for producing heavy strains.

The primary element of the improved organism or the element to which the power is applied primarily is a lever, and the ultimate element of said organism is a revoluble part, such as a wheel, a drum, a shaft, a disk, or the like. An incident of the operation of the device is that the oscillating or reciprocating motion of the lever is during its transmission converted into rotary motion; but if the final application of the power does not require rotary motion the motion may be again converted by any of the well-known appliances for this purpose.

I am aware that organisms for accomplishing all that I have thus far described are old, a good example of such an organism being shown in United States Letters Patent No. 298,188, granted to myself and others May 6, 1884, and I therefore desire to have it understood that my present invention consists in those features of novelty that are hereinafter fully described with reference to the accompanying drawings, which are made a part hereof, and in which—

Figure 1 is a side elevation of an organism embodying the invention. Fig. 2 is a sec-

tional elevation thereof. Fig. 3 is a plan view thereof. Fig. 4 is a plan view thereof with some of the parts reversed and with the primary lever of the system omitted. Fig. 5 is a section thereof on the line 5—5, Fig. 2, looking in the direction of the arrow.

A represents the primary element, to which the power to be transmitted is applied. Preferably it takes the form of a short lever capable of being oscillated about a suitable fulcrum B, sustained by a suitable base C. The outer or receiving arm of this lever may be of any desired length, and to this end it is preferably provided with a socket a or other appropriate feature for the reception of an extension A'.

D is the ultimate element of the organism, or, in other words, the element to which the power is to be transmitted. As before stated, it may consist of any revoluble part; but for the purposes of this application I have shown it as consisting of a drum suitably mounted so as to be capable of being revolved. To this end it is provided with a portion d in the nature of a journal, which occupies a suitable bearing in the base C, and with a flange d', that is engaged by overhanging brackets E, that are secured to the base, the arrangement being such that the drum is capable of free rotary movement, but incapable of end-wise movement relatively to the base.

F is a ring or collar arranged with its axis coincident with the axis of the drum D and mounted so as to be capable of rotating independently of the drum. Preferably it is mounted upon the drum and is sustained by the shoulder resulting from the flange d'.

G is a lever fulcrumed to the ring F at H. The inner end of this lever is shaped to form a cam I, which is adapted to engage the drum D when the lever is moved about its fulcrum in one direction and to be disengaged therefrom when the lever is moved about its fulcrum in the opposite direction. In practice the actual movement of the lever about its fulcrum is very slight. A very slight movement of it in the direction of the arrow in Fig. 3 of the drawings will bring the cam into engagement with the drum, and thereafter the drum and the ring F will partake of the movement of the lever so long as it continues to move in this direction. A very slight

movement of it in the opposite direction disengages the cam from the drum and brings the lever into engagement with a stop J, carried by the ring F, and thereafter the ring 5 will partake of the backward movement of the lever. It will be observed that repetitions of these movements of the lever will cause the drum D to be rotated in the direction of the arrow applied to it in Fig. 3 of the 10 drawings.

The outer end of the lever G has pivotal engagement with the lever A, and to this end the outer end of the lever G may be bifurcated and the lever A provided with a stud 15 K, which occupies the groove or opening between the two branches of the bifurcated end of the lever G, so that by oscillating the lever A about its fulcrum B the lever G is moved.

The patent above referred to shows an 20 organism comprising a revoluble part which is the equivalent of the part D herein shown and described, a primary lever which is the equivalent of the lever A herein shown and described, and means for transmitting movement from the short arm of the primary lever to the revoluble part, so that in what I have so far described the invention resides in the novel features for transmitting the movement from the shorter arm of the lever 25 A to the drum D.

The mechanism thus far described is such that the movement of the lever A in one direction only is transmitted to the drum D, its movement in the opposite direction being 30 used in the recovery of the clutching and transmitting mechanism. In order to transmit the movement of the lever A in both directions to the drum, and thereby impart to the latter a practically continuous rotary motion, the parts lettered F to K, inclusive, are 35 duplicated, similar duplicated parts being indicated by similar letters of reference, with the prime-mark added to the parts that have not thus far been described in detail. The 40 construction and mode of operation of the parts F' to K', inclusive, are precisely the same as the construction and mode of operation of the parts F to K, inclusive, with the exception that the levers G and G' are connected with the lever A upon opposite sides 45 of its fulcrum B, so that said levers G and G' always move in opposite directions. With the complete organism thus constructed every 50 movement of the primary lever A is transmitted to the drum D, and the differentials of the several levers are such that the force is greatly multiplied in its transmission. My 55 invention relates to the organism thus described and not to the means for applying the movement of the drum D. This means may, however, consist of a screw L, which is carried by the drum and may work through a 60 fixed nut in the upper cross-head of the press, the material to be pressed being in this case disposed between the base C and the platen or bed-plate. When the resistance to the 65 rotation of the drum D is only slight and the

drum must be rotated a considerable number of times in order to bring the parts to positions in which the resistance to the rotation 70 of the drum is materially increased, the lever A may be disconnected from the levers G G' and the power for rotating the drum applied directly to one or the other of said levers G G'. In this connection the lever itself may 75 be seized or an extension, such as A', may be applied to it either by inserting the extension in the bifurcated end of the lever G or into a socket g in the lever G'. This manner of manipulating the device is shown in Fig. 80 4. This figure also shows the lever G' inverted and reversed, so that it will rotate the drum in the direction opposite the arrow in Fig. 3. This reversibility of the levers G and G' is necessary in order to turn the drum in 85 the reverse direction for the purpose of retracting the screw L or otherwise removing or releasing the pressure produced by the operation of the device.

It will be observed that by connecting the 90 levers G and G' to the lever A upon opposite sides of its fulcrum one of said levers G G' is necessarily longer than the other. This being so, if the studs K and K' are placed at the same distance from the center of oscillation of a lever A the shorter lever will move through a greater arc than the longer lever. In order to avoid this and make the resistance to the movement of the lever A equal in both directions, the shorter one of the two 95 levers G G' is connected to the lever A at a point somewhat nearer the center of oscillation of said lever A than is the longer one of said levers G G'.

It will be observed that, as shown in the 100 drawings, that portion of the drum D which is engaged by the lever G is of somewhat greater diameter than the portion that is engaged by the lever G'. This is for the sole purpose of providing a shoulder for the ring F' to 105 rest upon and does not in any way affect the operation of the device, because when the cams of the levers G G' are in engagement with the drum said levers no longer have the characteristics of levers, but become in their nature 110 rigid arms projecting from the drum and moving about a center which is 115 the geometrical axis of the drum.

Having described my invention, what I 120 claim as new therein, and desire to secure by Letters Patent, is—

1. The combination with a revoluble part, of two levers adapted to be brought to the same radial position with respect to the axis of motion of said revoluble part and to be 125 moved in both directions from said position, means for non-rotatively connecting each of said levers with said revoluble part when moved in one direction and disconnecting them therefrom when moved in the opposite 130 direction, a third lever adapted to be brought to the radial position aforesaid, and means connecting the two levers first aforesaid with the third lever upon opposite sides of its ful-

erum, whereby the movement of the third lever causes the two levers first aforesaid to move in opposite directions, substantially as set forth.

- 5 2. The combination with a revolute part, of two independently-revolute rings or collars, two levers fulcrumed upon said rings or collars and having means for engaging said revolute part when moved in one direction 10 and disengaging it when moved in the opposite direction, a third lever, and means connecting the two levers first aforesaid with the third lever upon opposite sides of its fulcrum, whereby the movement of the third lever 15 causes the two levers first aforesaid to move in opposite directions, substantially as set forth.
3. The combination with a revolute part, of two independently-revolute rings or collars, two levers fulcrumed upon said rings or 20 collars and having means for engaging the revolute part aforesaid when moved in one direction and disengaging it when moved in the opposite direction, and a third lever to which the two levers first aforesaid are connected upon opposite sides of its fulcrum, 25 substantially as set forth.
4. The combination with a revolute part, of a pair of independently-revolute rings or collars, a pair of levers each fulcrumed to 30 one of said rings or collars and each having a cam adapted to engage said revolute part

when moved in one direction and to disengage it when moved in the opposite direction, said levers being reversible, stops carried by said rings or collars and disposed in the paths 35 of said levers, a third lever, and means connecting the levers first aforesaid with the third lever upon opposite sides of its fulcrum, substantially as set forth.

5. The combination with a drum, of a pair 40 of rings or collars mounted thereon so as to be revolute independently thereof, a pair of levers each fulcrumed to one of said rings or collars and each having a cam adapted to engage the drum when moved in one direction 45 and disengage it when moved in the opposite direction, a third lever, and means for connecting the levers first aforesaid with the third lever upon opposite sides of its fulcrum, substantially as set forth. 50

6. The combination with a revolute part, of two levers, means for transmitting the movement of said levers to said revolute part, and a third lever to which the two levers first aforesaid are connected upon opposite sides of its fulcrum and at different distances from its center of movement, substantially as set forth. 55
